UNITED STATES PATENT OFFICE.

EDWIN S. THURBER, OF BOSTON, MASSACHUSETTS.

HORSESHOE.

SPECIFICATION forming part of Letters Patent No. 270,154, dated January 2, 1883.
Application filed October 10, 1882. (No model.)

To all whom it may concern:

Be it known that I, EDWIN S. THURBER, of Boston, in the county of Suffolk, of the State of Massachusetts, have invented a new and useful Improvement in Horseshoes; and I do hereby declare the same to be described in the following specification, and represented in the accompanying drawings, of which—

Figure 1 is a bottom view, Fig. 2 a front view, 10 and Fig. 3 a longitudinal section, of a horseshoe provided with my invention, the nature of which is defined in the claims hereinafter presented.

The improvement is to enable the shoe to be 15 readily either expanded or contracted to fit the hoof of a horse, and to expand laterally with the hoof as it may grow or increase in size.

In carrying out my invention, the shoe is made in two sections or halves, A A, provided 20 with the usual creases, *a*, and nail-holes *b*, and these sections, at the toe of the shoe, are connected by a spiral spring, B, screwed into each of them and extended from one to the other of them, and going through an elastic or vulcanized india-rubber washer, C, arranged between them, all being substantially as represented.

There may be screwed lengthwise into the spring, in each of the parts thereof, within either of the sections A A, an elastic metallic

rod, D, such serving to stop the end of the 30 spring.

The elastic washer not only fills the joint between the two sections and protects the spring, but enables such spring to yield where it is between the sections when the heels of the sections are moved either toward or away from each other.

I claim—

1. The shoe made in two sections, A A, and connected at the toe by a spiral spring screwed 40 into both of them and arranged therewith, substantially as set forth.

2. The shoe composed of the two sections, the elastic washer, and the spiral spring, ar- 45 ranged as set forth.

3. The shoe made in sections A A, connected by a spiral spring screwed into or se- 45 cured to each, and plugged at its ends, as set forth.

4. The shoe made in sections A A and con- 50 nected, as described, by a spiral spring plugged at its ends and going through an elastic washer arranged between the toe ends of such sections, all being substantially as set forth.

EDWIN S. THURBER.
